(57) **CLAIM**

The ornamental design for a toilet lid cushion, as shown and described.

DESCRIPTION

FIG. 1 is a perspective view of a first embodiment of toilet lid cushion showing my new design covering the lid of a toilet;

FIG. 2 is a front view thereof;

FIG. 3 is a right side view thereof;

FIG. 4 is a top view thereof;

FIG. 5 is a left side view thereof;

FIG. 6 is a rear view thereof;

FIG. 7 is a bottom view thereof;

FIG. 8 is a perspective view of a second embodiment showing my new design;

FIG. 9 is a front view thereof;

FIG. 10 is a right side view thereof;

FIG. 11 is a top view thereof;

FIG. 12 is a left side view thereof

FIG. 13 is a rear view thereof; and,

FIG. 14 is a bottom view thereof.

The toilet seat portion shown by broken lines in FIGS. 1 and 8 of the drawing represent environment subject matter and the seat portion shown in broken line forms no part of the claimed design.
